JOURNAL BOX LID

Donald D. Bryant, Huntington, W. Va.

Application November 28, 1950, Serial No. 197,997

17 Claims. (Cl. 308—47)

1

This invention is a novel journal box lid, and the principal object thereof is to provide a lock-seal lid which will dispense with the necessity of using coiled springs, but which will open easily and will lock itself shut, will seal the rough cast face of the opening of the journal box, will fit any standard bulk car door or any standard journal box, will be absolutely dust and moisture proof, will not vibrate, and can be more easily applied than other types of lids now in use.

The present invention is an improvement upon the lock-seal lid shown and described in my U. S. Letters Patents No. 2,481,076 dated September 6, 1949; No. 2,498,245 dated February 21, 1950; and No. 2,501,494 dated March 21, 1950.

All locomotive tenders, passenger cars and freight cars in use in railroad and other rail transportation systems have a removable journal brass or bearing in the journal box which is kept lubricated by packing or other suitable material to prevent generation of heat or friction between the journal and bearing. Each journal box with its packing is closed on its inner end by a dust-guard seal, while its outer end is closed by a journal box lid.

It is necessary to form the lid so that same can be readily opened and closed for packing and journal bearing inspection at any time, and to repack or set up or readjust the packing to its proper level, and to refill the journal box with oil.

A lid, to be efficient, should be opened easily and should completely seal the rough cast face of the journal box around the opening, which face is not machined. Moreover, the lid should not vibrate, as this would cause undue wear on the lid, and the cast face. It should, moreover, remain moisture-proof and dust-tight at all times.

The box lids as at present used do not fit properly nor tightly against the opening in the journal box, the face of which has been cast but not machined, and hence do not make true contact between the journal box casting and the inside of the applied lid. Thus, dirt, moisture and other foreign material is permitted to enter the journal box between the face of the box and the lid, the foreign material contaminating the packing and oil, thus causing excessive journal bearing wear.

My new and novel journal box lid is designed to eliminate the above undesirable conditions which are detrimental to equipment, also to eliminate the excessive lift or pull which is required to open the present type lids which depend upon pressure to force the lid shut, this

2

pressure being usually exerted by different types of coiled springs exerting force at the outer or inner side of the lid in an attempt to hold it shut and to make the lid fit closer to the journal box to render same dustproof. The spring pressure on some types of lids is so strong that it is difficult and often physically impossible for a man of average strength to open the same. Each box must be opened and inspected before the train leaves its terminal, and the boxes are often not inspected because of excessive spring pressures.

When the face of the casting is rough cast, or uneven, the lid cannot and will not fit, regardless of said spring pressure, the lid merely riding on the highest point of the casting and not contacting the entire face. When such high point is worn, due to vibration and constant opening and closing of the box for inspection, the lid closes partly under its closing pressure and the hinge pin becomes worn, also the casting lug hole as well as the lid hinge. Thus, by inherent defects, the present type lid allows dirt, abrasive, moisture, sand and other foreign elements to enter into the journal box, especially when the train is in motion. This foreign material fouls the packing and oil, causing friction between the bearing and journal and resulting in undue wear of moving parts, thus causing unnecessary expense and labor. This friction is often the cause of hot boxes, train delays, derailments, causing property loss, endangering the lives of train crews and the traveling public. In the northern section of the United States snow often covers the tops of the journal boxes and the need is then even greater for a lock-seal lid.

Bulk cars, which carry grain, sugar, feed, and other bulk material, usually are provided with doors in their tops, as many as four or more doors being used, said doors being substantially identical in construction to the front end of a journal box, but of larger size, the doors having hinge lugs and pins. My lock-seal lid may also be used on such doors without change, except for size, to exclude dirt and moisture, to prevent vibration, and to provide other advantages similar to those above stated with respect to its application to journal boxes.

The principal objects of my present invention are to provide a journal box lid so designed that it is much lighter in weight than the present type lids, it does not use the hinge lug face to hold the lid either open or closed in the conventional positions; the hinge pin may be entered or removed from either side and locks itself in

place automatically; the lid liner may be removed or replaced at any time; the pressure on the lid is inserted downwardly from a small pin when the lid is closed and is held closed by maximum pressure on the lid when the lid is closed so that it will seal the journal box face and will be dust and moisture-proof even if the lug flats are worn entirely out because of the fact that same does not utilize the hinge lug flats; the liners being preferably made of oil-resistant neoprene or the like, while the lid is made of steel and manufactured by stamping process. Also, a further object is to provide a lid so designed that a minimum lifting force may be applied thereto to initially open the lid, said force diminishing to approximately zero when the lid is about half opened, whereupon the force increases and acts to snap the lid into opened position upon further raising of the lid, said force maintaining said lid in fully opened position. Also a further object is to provide a lid so designed that a minimum pulling force may be applied thereto to initially close the lid, said force diminishing to approximately zero when the lid is about half closed, whereupon the force increases and acts to snap the lid closed upon further closing of the lid, said force maintaining the lid in fully closed position. I will explain the invention with reference to the accompanying drawings, which illustrate one practical embodiment thereof to enable others familiar with the art to adopt and use the same; and will summarize in the claims the novel features of construction, and novel combinations of parts, for which protection is desired.

In said drawings:

Fig. 1 is a vertical section through the outer end of a standard journal box, showing my novel lid, including the frame and cover plate applied thereto, and showing the cover plate in closed position, said section being taken on the line 1—1, Fig. 2, as indicated by the arrow 2—2; Fig. 3 is a view similar to Fig. 1, but showing the cover plate in open position; Fig. 4 is an enlarged side elevation of one of the roller cams; and Fig. 5 is a top plan view of the cam shown in Fig. 4.

The drawings show my novel lid applied to a standard journal box, for illustrative purposes only, the journal box J per se forming no part of my present invention. As shown in Fig. 1, the standard journal box J has a rough cast open outer end, over which opening my novel lid is attached, the opening being usually formed during the casting operation, and being left unfinished. The journal box J is provided with a standard hinge lug J' on the top thereof above the open end, in the customary manner.

Around the opening in the journal box J is a frame member 1 of rectangular shape or other shape conforming with the shape of the opening in the journal box J, said frame being of greater width and height than the thickness of the lip around the opening of the journal box, as shown more particularly in Figs. 1 and 3; said frame

At the lower end of frame 1 disposed at the center thereof is an inwardly and downwardly curved resilient spring tongue 1a (Figs. 1 and 3) extending within the lower end of the opening in the journal box J and having its free end engaging the inner lower curved wall of said box J, so as to conform to the casting thickness and any irregularities in casting form, and whereby

the lower end of the frame 1 will be prevented from moving away from the lower portion of the opening of the box J.

At the upper end of the frame 1 is a pair of resilient hinge eyes 1b, preferably formed of resilient metal bent to such shape that the axes of the eyes 1b are normally slightly offset outwardly from the axes of the bore J2 of the hinge lug J', whereby when the hinge pin 2 is passed through the eyes 1b and through the bore J2 of hinge lug J', the sheet metal eyes 1b will be deflected so as to forcibly pull the upper portion of the frame 1 towards and against the upper port of the opening in the journal box J, the action of the eyes 1b and the resilient tongue 1a thereby serving to tightly clamp the upper and lower ends of frame 1 against and across the opening in the journal box J.

In order that the hinge pin 2 may be entered from either side of the hinge lug J' and will lock itself in place, the eyes 1b of frame 1 are preferably split as shown more particularly in Fig. 2, and the outer portions 1bx are crimped inwardly to engage annular grooves 2a in the pin 2 under the portions 1bx to prevent the pin 2 from normally shifting axially of the hinge bore J2.

As shown, the inner face of frame 1 is provided with a peripheral groove 1c (Figs. 1 and 3) adapted to hold therein a gasket 3 of substantial thickness, preferably formed of oil-resistant neoprene or the like, adapted to contact squarely the lip around the opening of the journal box J, so as to form an effective seal, as indicated in Figs. 1 and 3. Due to the hinges 1b, 1bx, and the tongue 1a, the gasket 3 is seated firmly at all times against the lip of the opening of the journal box J, to prevent passage of dust and moisture therewith.

At the upper end of frame 1 are a pair of spaced outwardly rolled eyes 1e adapted to receive a hinge pin 4 for a cover plate 5. Cover plate 5 is provided at its upper end with rolled eyes 5e (Figs. 1, 2 and 3) adapted to engage the hinge pin 4, the outer ends of the eyes 5e being of reduced width and extending beyond the ends of the pin 4, and being flanged or bent over the ends of pin 4, after the latter has been inserted in place, to hold pin 4 in such position. The cover plate 5, as shown more particularly in Figs. 1, 2 and 3, is of substantially the same size and area as the frame 1, the same having inturned flanges 5a on its top, bottom and sides, and having a flange 5b on its under side of same shape but smaller than the flanges 5a, the space between the flange 5b and the flanges 5a being adapted to hold therebetween a gasket 6 of oil-resistant neoprene, or the like, which projects beyond the flanges 5a, 5b so as to seat squarely upon the peripheral face of the frame 1, as shown more particularly in Fig. 1, to prevent entrance of dust and moisture between the cover plate 5 and the frame 1.

Across the front of cover plate 5 is a Y-shaped metallic plate 7, the base of which is riveted as at 8 to cover 5, the lower end of the plate 7 having an extension 7a which is offset from the plane of the base 7, as at 7b, so as to conform with the contour of the outer face of cover 5. Extension 7a extends beyond the lower edge of plate 5 and its lower edge is split as at 7c, the outer edge at one side of the split 7c being bent on an arc in one direction as at 7d, while the metal at the opposite side of the split 7c is rolled in the opposite direction as at 7e, Figs. 1 and 2.

The upper edge of the base of plate 7 ter-

minates somewhat above the horizontal center line of the cover plate 5, and the legs 7f and 7g are offset outwardly of the base 7 as shown at 7h in Figs. 1 and 3, and the legs extend upwardly and outwardly of the cover 5 when closed to a point approximately opposite the hinge pin 2 of the journal box. Preferably the sides of legs 7f, 7g are flanged toward the cover 5 for the major portions of their length, as indicated at 7i in Figs. 1 and 3 for the purpose of stiffening the said legs without however preventing same from flexing.

Mounted upon the frame 1 at the upper end thereof are upwardly and outwardly extending cams 9, shown more particularly in Figs. 4 and 5, the same having flanged feet 9a which are riveted as at 10 to the bases of the hinge members 1b of frame 1, as shown in Figs. 1 and 3, said lugs having bores 9b therein for the passage therethrough of hinge pin 4 of the cover 5, the studs 9 thus serving as additional bearings for said hinge pin. The outer ends of the studs 9 are slotted as at 9c, Fig. 5, and rollers 12 are housed in the slots and journaled on pins 13, the rollers 12 extending beyond the ends of the cams 9 and being in constant contact with the inner faces of the resilient legs 7f, 7g as shown in Figs. 1 and 3.

By the above construction when the cover 5 is closed, as in Fig. 1, the rollers 12 engage the outer portions of the legs 7f, 7g, and owing to the resiliency of the legs the cover 5 will be maintained by maximum spring pressure closed against the frame 1. When opening the cover a tool or hook may readily be engaged with the lower end of the extension 7a of plate 7 and by an upward and outward pull the cover 5 will open, the legs 7f, 7g yielding while maintaining contact with the cam rollers 12, and the closing pressure decreasing until the cover has reached a substantially half open position. Upon further upward pull on the cover an opening or increasing pressure will be exerted by the legs 7f, 7g on the rollers 12 to cause the cover 5 to spring open into position shown in Fig. 3, and cover 5 will remain open in said position.

My lid therefore is so designed that a lifting force may be applied thereto to initially cause opening of the cover, said force diminishing to approximately zero when the cover is about half open, while upon further raising of the lid, the force increases and acts to snap the cover into fully opened position, said force maintaining the cover in fully opened position; also a pulling force may be applied to the open cover to initially cause closing of the cover, said force diminishing to approximately zero when the cover is about half closed, whereupon the force increases and acts to snap the cover closed upon further closing movement of the cover, said force maintaining the cover in fully closed position.

By the above construction, when the parts are in the position shown in Fig. 1, the eyes 1b of frame 1 and tongue 1a will securely hold the frame 1 against or in contact with the lip around the opening in the outer end of the journal box J. At the same time the gasket 6 of the cover plate 5 will be maintained in firm engagement with the outer peripheral face of the frame 1 by means of the hinge eyes 5e and the rollers 12. When, however, the handle 7a is pulled outwardly, the cover plate 5 will swing upwardly and upon reaching its half open position will snap into fully open position in which same is disposed at an angle substantially normal to the

plane of frame 1, as shown in Fig. 3, to permit the journal box to be serviced without necessitating the operator holding the cover plate 5 in open position.

6. By the above construction, a journal box lid is provided which is much lighter in weight than the present type lids; also a journal box is provided which does not use the usual hinge lug flats to hold the cover plate in either open or closed position. The gasket 6 may be removed or replaced at any time. The pressure on the cover plate 5 is inserted downwardly from the small pin 4 when the cover plate is closed, and will be forced tightly shut at the bottom by spring action of the rollers 12 engaging the resilient legs 7f, 7g of the cover 5.

The journal box lid will seal the journal box face so as to maintain same dust and moisture-proof even if the hinge lug flats of the journal box are worn entirely away, since my arrangement does not use these hinge lug flats on the journal box casting although the cover plate 5 opens and closes in the conventional manner. The gaskets 3 and 6 may be of oil-resistant neoprene or the like, while the cover may be of steel and may be manufactured readily by a stamping process.

I do not limit my invention to the exact form shown in the drawings, for obviously changes may be made therein within the scope of the claims.

I claim:

1. In combination with a journal box or the like, having a bottom wall sloping upwardly and outwardly and terminating at an opening in the outer end thereof, a hinge lug on the top of the box; a hinge pin in said lug; a lock seal lid, comprising a frame hinged on said pin and having an opening therein corresponding in area with the box opening; a gasket around the inner face of the frame adapted to engage the end of the box around said opening; means for maintaining the frame in tight contact with the box end; a second hinge pin mounted on the outer face of the frame adjacent the top thereof; a cover plate hinged on the second pin and adapted to overlie the frame; a second gasket around the inner face of the cover plate projecting beyond said inner face and adapted to contact the outer face of the frame; a cam mounted on the frame projecting outwardly of the hinge lug of the journal box; and resilient means on the cover plate yieldably constantly engaging the cam for locking the cover plate in tight contact with the frame when the cover plate is closed and for holding the cover plate in open position when the cover plate is opened.

2. In a combination as set forth in claim 1, said cam having a bore therethrough through which the second hinge pin passes and serving as a support for the second hinge pin.

3. In a combination as set forth in claim 1, said resilient means comprising a base plate secured to the cover plate and having a leg portion offset from the plane of the base plate contacting the said cam, the sides of the leg portion adjacent the cam being flanged for the purpose of locally stiffening same.

4. In a combination as set forth in claim 1, said frame maintaining means comprising a downwardly and inwardly inclined resilient tongue at the lower end of the frame adapted to enter the box opening and to contact the inclined bottom wall of the box adjacent the opening, to maintain the lower end of the frame in tight contact with the end of the box.

5. In a combination as set forth in claim 1, said frame maintaining means comprising hinge eyes on the frame at opposite sides of the first hinge lug and secured to the upper end of the frame by resilient metal straps, the eyes being normally offset from the frame a distance less than the actual distance of the upper end of the frame from the axis of the hinge pin, whereby the straps will be flexed when the hinge pin passes through the eyes, to forcibly draw the upper end of the frame towards the box.

6. In a combination as set forth in claim 1, said frame maintaining means comprising hinge eyes on the frame at opposite sides of the first hinge lug and secured to the upper end of the frame by resilient metal straps, the eyes being normally offset from the frame a distance less than the actual distance of the upper end of the frame from the axis of the hinge pin, whereby the straps will be flexed when the hinge pin passes through the eyes, to forcibly draw the upper end of the frame toward the box, said eyes being transversely split, and having crimped portions at one side of the split engaging underlying annular recesses in the hinge pin.

7. In combination with a journal box or the like, having a bottom wall sloping upwardly and outwardly and terminating at an opening in the outer end thereof, a hinge lug on the top of the box; a hinge pin in said lug; a lock seal lid, comprising a frame hinged on said pin and having an opening therein corresponding in area with the box opening; a gasket around the inner face of the frame adapted to engage the end of the box around said opening; means for maintaining the frame in tight contact with the box end; a second hinge pin mounted on the outer face of the frame adjacent the top thereof; a cover plate hinged on the second pin and adapted to overlie the frame; a second gasket around the inner face of the cover plate projecting beyond said inner face and adapted to contact the outer face of the frame; a pair of cams mounted on the frame projecting outwardly of the hinge lug of the journal box; rollers journaled in the outer ends of the cams; and resilient means on the cover plate yieldably constantly engaging the cams for exerting pressure for locking the cover plate in tight contact with the frame when the cover plate is closed and for exerting pressure for holding the cover plate in open position when the cover plate is opened, said pressure diminishing to zero when the cover plate is approximately half open or half closed.

8. In a combination as set forth in claim 7, each cam having a bore through which the second hinge pin passes and serving as a bearing for the second hinge pin.

9. In a combination as set forth in claim 7, said resilient means comprising a Y-shaped member having a base plate secured to the cover plate and having parallel leg portions offset from the plane of the base plate contacting the said rollers, the sides of the leg portions adjacent the rollers being flanged for the purpose of locally stiffening the same.

10. In a combination as set forth in claim 7, said frame maintaining means comprising a downwardly and inwardly inclined resilient tongue at the lower end of the frame adapted to enter the box opening and to contact the inclined bottom wall of the box adjacent the opening, to maintain the lower end of the frame in tight contact with the end of the box.

11. In a combination as set forth in claim 7, said frame maintaining means comprising hinge eyes on the frame at opposite sides of the first hinge lug and secured to the upper end of the frame by resilient metal straps, the eyes being normally offset from the frame a distance less than the actual distance of the upper end of the frame from the axis of the hinge pin, whereby the straps will be flexed when the hinge pin passes through the eyes, to forcibly draw the upper end of the frame towards the box.

12. In a combination as set forth in claim 7, said frame maintaining means comprising hinge eyes on the frame at opposite sides of the first hinge lug and secured to the upper end of the frame by resilient metal straps, the eyes being normally offset from the frame a distance less than the actual distance of the upper end of the frame from the axis of the hinge pin, whereby the straps will be flexed when the hinge pin passes through the eyes, to forcibly draw the upper end of the frame towards the box, said eyes being transversely split, and having crimped portions at one side of the split engaging underlying annular recesses in the hinge pin.

13. A lock-seal lid, comprising a frame having hinge eyes at its upper end and having an opening therein; a gasket around the inner face of the frame, a downwardly inclined resilient tongue at the lower end of the frame; a hinge pin mounted on the outer face of the frame adjacent the top thereof; a cover plate hinged on the said pin and adapted to overlie the frame; a second gasket around the inner face of the cover plate projecting beyond said inner face and adapted to contact the outer face of the frame; a pair of cams mounted in the frame projecting outwardly of the hinge pin, rollers journaled in the outer ends of the cams; and resilient means on the cover plate in tight contact with the rollers when the cover plate is closed and for exerting pressure for holding the cover plate in open position when the cover plate is opened, said pressure diminishing to zero when the cover plate is approximately half open or half closed.

14. In a device as set forth in claim 13, each cam having a bore through which the hinge pin passes and serving as a bearing for the hinge pin.

15. In a device as set forth in claim 13, said resilient means comprising a Y-shaped member having a base plate secured to the cover plate and having parallel leg portions offset from the plane of the base plate contacting the said rollers, the sides of the leg portions adjacent the rollers being flanged for the purpose of locally stiffening the same.

16. In a device as set forth in claim 13, said hinge eyes being secured to the upper end of the frame by resilient metal straps.

17. In a device as set forth in claim 13, said eyes being transversely split, and having crimped portions at one side of the split.

DONALD D. BRYANT.
